UNITED STATES PATENT OFFICE

171,842

CHILDREN'S WHEELED COASTER

Harold E. Cress, Renfrew, Pa.

Application April 20, 1953, Serial No. 24,585

Term of patent 3½ years

(Cl. D34—15)

To all whom it may concern:

Be it known that I, Harold E. Cress, have invented a new, original, and ornamental design for a Children's Wheeled Coaster, of which the following is a specification, reference being had to the accompanying drawing, forming a part hereof.

Fig. 1 is a side view of the children's wheeled coaster embodying my new design;

Fig. 2 is a plan view thereof; and

Fig. 3 is a fragmentary front end view thereof, a portion of the seat post being broken away for convenience of illustration.

I claim:

The ornamental design for a children's wheeled coaster, as shown.

HAROLD E. CRESS.
